CLAIM

I claim the ornamental design for a user interface for a portion of a display screen targeted for live events or travel, as shown and described.

DESCRIPTION

The FIGURE is a front view of a user interface for a portion of a display screen targeted for live events or travel showing my new design.

The broken line showing of an electronic device is shown for environmental purposes only and is not claimed. Only what is contained within the solid lined frame is claimed.

See application file for complete search history.
